No. 762,464.

PATENTED JUNE 14, 1904.

H. BORGmann.

WINDOW SASH CASING.

APPLICATION FILED SEPT. 10, 1903.

NO MODEL.

UNITED STATES PATENT OFFICE.

HENRY BORGmann, OF WASHINGTON, DISTRICT OF COLUMBIA.

WINDOW-SASH CASING.

SPECIFICATION forming part of Letters Patent No. 762,464, dated June 14, 1904.

Application filed September 10, 1903. Serial No. 172,670. (No model.)

To all whom it may concern.

Be it known that I, HENRY BORGmann, a citizen of the United States, residing at Washington, in the District of Columbia, have invented a new and useful Window-Sash Casing, of which the following is a specification.

My invention relates to window-sash casings, and has for its object to provide a device of this character of simple construction which will permit of the ready removal of the window for cleaning or other purposes.

To these ends the invention comprises the novel details of construction and combination of parts more fully hereinafter described.

In the accompanying drawings, Figure 1 is a side sectional elevation of a portion of a window embodying my invention. Fig. 2 is a similar view, on an enlarged scale, showing the lower end of the movable section and its supporting means. Fig. 3 is a section on the line 3-3 of Fig. 2. Figs. 4, 5, and 6 are detail views. Figs. 7 and 8 are similar views of the sash-cord-holding device.

Referring to the drawings, 1 designates the upper and 2 the lower sections or sashes of the window, which travel, respectively, in a rear guide 3 and front guide 4, provided in the casement 5, these parts being, except as hereinafter specified, of the usual or any preferred construction and material.

The guide 4 consists of a rear wall formed by the division-strip 6, a front wall formed by the front molding 7, and an end wall 8, forming the front wall of a weight opening or channel 9, provided in the casement and separated into two compartments by a partition 10, attached in any suitable manner to the rear wall 11, the said compartments of the channel being designed for the weights of the upper and lower window-sections, respectively. The end wall 8 of the guide is made up of a lower fixed section 12, an upper fixed section 13, and an intermediate movable section 14 of a length slightly greater than the height of the window-section 2 and meeting the upper and lower sections, with which it is vertically alined by miter-joints 15. The division-strip 6, constituting the rear wall of the guide, is also provided with a movable section 16, attached to and carried by the section 14, while the front

molding 7 projects at its rear end into the path of and constitutes a stop 17 for limiting the outward movement of the section 14.

The movable section 14 is held in engagement with the fixed sections 12 13 and is movably sustained by a pair of devices 18 19, engaged, respectively, with the upper and lower fixed sections. As these supporting devices are identical in construction and operation, I will describe but one in detail, in which 20 indicates a primary member in the form of a tubular barrel or thimble extending transversely through the wall of the fixed section and having at its forward end a peripheral outstanding flange 21, which limits its rearward movement, at its rear end a longitudinal inwardly-extending opening or recess 22, and in its front wall a central keyhole-opening 23, the purposes of which parts will presently appear.

24 indicates the secondary member of the supporting device, said member being preferably composed of a cylindrical head or portion 25, having a central internally-threaded opening 26, which normally alines with the opening 23, and a right-angularly-extending arm or portion 27, which extends to the movable section 14 and is attached to the latter by a screw passing through an opening 28, the arm being provided at its outer end with a sharpened lateral projection 29, designed to bite into the material of section 14 for maintaining the latter and the arm 27 in proper fixed alinement.

The members 20 24 of each supporting device are movably connected by an element 30 in the form of a screw extended through the opening 23 and in threaded engagement with the opening 26, said screw being provided at its outer end with a wing-head 31, having a tool-seat 32. The head 31 lies within a cavity or socket 33, provided for its reception at the outer end of member 20, while upon the screw 30 is a lateral lug or projection 34, spaced from the head 31 and designed to bear upon the inner face of the end wall of member 20. It is obvious from this construction that when the screw 30 is rotated either by engagement of the fingers of the operator with the head or of a tool with the seat 32 the member 24

will be moved outward, carrying with it the section 14 of the guide, to the position indicated by dotted lines in Fig. 2, when the section 16 of strip 6 will be moved from its position in rear of sash 2, thus permitting of the latter being shoved inward at one side and readily disengaged from the guide at the opposite side of the casement, said latter guide being, of course, of the usual construction.

10 It is to be understood, of course, that for moving the section 14 inward both of the devices 18 19 will be manipulated in the manner just explained and that when the section moves inward such movement will be limited 15 by an adjustable stop 35, preferably in the form of an angle-screw engaged with the lower fixed section 12, this screw being in alinement with the weight-channel partition 10, whereby it will be out of the path of and will not 20 interfere with the movements of the weights.

To insure the window-section 2 when removed from the casing being readily freed from its weight-cords, I provide, as illustrated in Figs. 7 and 8, a weight-cord-engaging device 25 vice in the form of a short tubular member 36, designed to be driven horizontally into the side bar of the window-sash, said member being provided with a circular cord-receiving opening 37, having a lateral tangentially-disposed entrance mouth or slot 38. In attaching the cord (indicated by dotted lines in Fig. 8) I form at its outer end, as usual, a knot, which when the cord is passed through slot 38 to opening 37 lies beneath the latter within 35 the member.

In practice the member 20 is locked against non-rotation by pin 40, and the longitudinal slot 22 receives the arm 27 of member 24 when the parts are in normal position, so that by 40 making the slot, as herein shown, of a depth considerably greater than the thickness of the arm the device is adapted for attachment to

casings in which the wall 8 varies in thickness.

From the foregoing it will be seen that I 45 produce a device of simple construction which will be efficient in operation and permit the ready removal of the window-section. In attaining these ends I do not limit myself to the precise details herein set forth, inasmuch 50 as minor changes may be made therein without departing from the spirit of the invention.

Having thus described my invention, what I claim is—

1. The combination with a window and its 55 casing, of a sash-guide carried by the latter, said guide having a movable section operable for permitting removal of the sash, and devices for movably sustaining the section, said devices comprising each a tubular member 60 associated with the casing, a member associated with the section and having an internally-threaded opening, and a screw connecting said members.

2. The combination with a window and its 65 casing, of a sash-guide carried by the latter, said guide having a movable section operable for permitting removal of the sash, a member associated with the section and comprising an internally-threaded head and an attaching- 70 arm, a tubular member associated with the casing to receive the head and having a longitudinal recess for entrance of the arm, and an operating-screw connected with the tubular member and in threaded engagement with the 75 head.

In testimony that I claim the foregoing as my own I have hereto affixed my signature in the presence of two witnesses.

HENRY BORGmann.
